CLAIM

The ornamental design for a hose, as shown and described.

DESCRIPTION

FIG. 1 is a perspective view of a Hose showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof; and,

FIG. 7 is a bottom view.

The portion of the hose shown broken away is to indicate that no specific length of hose is claimed. The broken line showing is included for the purpose of illustrating portions of the article that form no part of the claimed design.
